Filed Jan. 5, 1961, Ser. No. 80,831
5 Claims. (Cl. 67—7.1)

This invention relates to a cigarette lighter and particularly to a cigarette lighter which is fired automatically simultaneously with an opening action of a hinged cap.

One object of this invention is to provide a cigarette lighter which may be fired without a manual rotation of an igniting wheel.

Another object of this invention is to provide a cigarette lighter which may be fired surely.

Still another object of this invention is to provide a cigarette lighter having a simple construction so as to be made easily.

Briefly stated in accordance with one aspect of this invention, there is provided a cigarette lighter comprising a throwable member, a pawl, an igniting wheel, and a pushing-up or cam member. The throwable member is pivotally mounted on a shaft and has a hole through which the top of the pawl is extended upwards to be fixed to the throwable member. The pawl is adapted to engage with the igniting wheel so as to rotate the latter when the throwable member pivots together with a cap. The igniting wheel is engaged with a flint loaded by a spring. The pushing-up member is arranged by the side of the flint and loaded by another spring so as to cam the throwable member and the pawl to rotate the igniting wheel, whereby the lighter is fired automatically when the cap is opened.

The invention will be better understood and other objects and additional advantages of the invention will become apparent upon perusal of the following description taken in connection with the drawings, in which:

FIG. 1 is a vertically sectional front view of an embodiment of this invention; and

FIG. 2 is a vertically sectional side view thereof taken along lines II—II of FIG. 1.

Referring more particularly to the drawings, the preferred embodiment of this invention will now be described; however, this description will be understood to be illustrative of the invention and not as limiting it to the particular construction shown and described.

There is casing 15 having a cap 1 which may turn on a hinge. A fuel reservoir 9 is accommodated inside the casing 15 and fixed thereto. A wind shield 16 is secured on the top of the reservoir 9. A throwable member 2 is pivotally mounted on a shaft fixed to the wind shield and is adapted to pivot simultaneously with the opening and closing actions of the hinged cap 1. The throwable member 2 is formed in a U-shape in its axial section and an igniting wheel 3 is mounted rotatably on the shaft within the throwable member 2. A ratchet wheel 4 is formed on a side of the igniting wheel 3 which is engaged with an elastic pawl 5 pivoted on the shaft. The top 6 of the pawl 5 extends upwards through a hole 7 provided in a side wall of the throwable member 2 and fixed thereto.

A flint is positioned at the top of a flint pushing tube 10 and is adapted to cooperate with the igniting wheel 3, so that when the cap 1 is opened the igniting wheel 3 is driven by the pawl 5 to fire the lighter. The tube 10 is secured to the reservoir 9 at its top and extended downwards within the casing 15. A nut 11 is screwed on the lower part of the flint pushing tube 10 which is threaded on its lower outer surface. Another U-shaped pushing-up or cam member 8 is provided around the tube 10, the latter being inserted slidably through a hole provided in the center of the pushing-up member 8. Two legs

2

of the pushing-up member 8 are extended upwards to push the lower edges of the two legs of the throwable member 2. The lower edges of the throwable member 2 are rounded, having protrusions towards the hinge, and 5 coact with the rounded tops of the pushing-up member 8. Then by the action of a coil spring 12 loading the pushing-up member 8 upwards against the nut 11, the throwable member 2 tends to turn in the counterclockwise direction in FIG. 1. It is preferable to thicken the lower edges of the throwable member 2 so as to secure 10 the engagement thereof with the top of the pushing-up member 8. Numeral 13 indicates a screw screwed inside the bottom of the flint pushing tube 10 so as to push the flint upwards conventionally. Numeral 14 indicates 15 a partition bordering the reservoir 9. Numeral 17 indicates a wick.

In operation, after the cap 1 is opened manually to an extent, the throwable member 2 is forced to turn together with the pawl 5, so as to rotate the igniting wheel 3 automatically, and simultaneously the cap 1 continues the opening action by the pushing action of the spring 12. When the igniting wheel 3 is rotated, the wick 17 is fired conventionally. Thus it becomes unnecessary to rotate the igniting wheel 3 manually. When the cap 1 is closed 25 manually, the coil spring 12 is compressed so as to secure the closed position of the cap 1. By virtue of the arrangement of the pushing-up member 8 and the coil spring 12 around the flint pushing tube 10, the whole construction becomes simpler so as to make this lighter more easily. 30 By virtue of the arrangement of the elastic pawl 5 inserted through the hole 7, the engagement of the pawl 5 with the ratchet wheel 4 is ensured, and the pawl 5 is made durable and may be fixed to the wall of the throwable member 2 durably and easily repairably.

While there is herein shown and described a preferred form of the present invention, I do not wish to be limited to the form herein particularly shown and specifically described, but rather intend that the invention shall include all reasonable equivalents thereof which will occur to those skilled in the art from the present disclosure.

What is claimed as new and desired to be secured by Letters Patent of the United States is:

1. In a lighter of the type including a casing, a fuel reservoir in said casing, a wick extending from the reservoir, an igniting wheel rotatably mounted on a shaft supported on the reservoir, a flint, means for biasing the flint into cooperable relationship with the igniting wheel: a cover hinged to said casing at an end thereof adjacent said shaft, for movement between open and closed positions; a relatively elongated throw member pivoted adjacent one end to said shaft and coupled to said cover for movement therewith, said one end of said throw member being formed with a cam surface eccentric to said shaft; a pawl pivoted on said shaft and anchored to said throw member, said pawl being cooperable with a ratchet on said igniting wheel to rotate the latter upon pivoting of said throw member; a cam member longitudinally slidably mounted in said casing for movement toward and away from said shaft, said cam member having a camming end engageable with said cam surface; and means biasing said cam member toward said shaft; said camming end, after a partial opening of said cover, coacting with said cam surface to bias cover to the open position to pivot said throw member to rotate said pawl and said igniting wheel to fire the lighter; said cam surface, upon closing of said cover, coacting with said camming end to move said cam member against the force of its biasing means.

2. In a lighter as claimed in claim 1, wherein said means for biasing the flint includes a flint tube mounting said flint; said cam member being apertured to receive said flint tube and being slidably mounted thereon.

3. In a lighter as claimed in claim 2, the lower portion of said flint tube being exteriorly threaded; said biasing means comprising a coil spring embracing said flint tube and engaged at one end with said cam member; and a nut threaded on said exteriorly threaded portion of said flint tube and engaged with the other end of said coil spring to adjust the bias of said cam member.

4. In a lighter as claimed in claim 1, said throw member being U-shaped and said shaft extending through apertures in the outer ends of the arms of the U; said outer ends being thickened; said cam member being U-shaped and having said camming end formed on the ends of its arms. 10

5. In a lighter as claimed in claim 4, wherein said means for biasing the flint includes a flint tube supporting said flint; said cam member having an apertured base slidably receiving said flint tube.
